UNITED STATES PATENT OFFICE.

LEWIS H. URNER, OF NEVADA, MISSOURI.

HARNESS-PAD PRESS.

SPECIFICATION forming part of Letters Patent No. 283,305, dated August 14, 1883.

Application filed April 30, 1883. (No model.)

To all whom it may concern:

Be it known that I, LEWIS H. URNER, a citizen of the United States, residing at Nevada, in the county of Vernon and State of Missouri, have invented certain new and useful Improvements in a Harness-Pad Press; and I do hereby declare that the following is a full, clear, and exact description of the same, reference being had to the annexed drawings, making a part of this specification, and to the letters and figures of reference marked thereon.

Figure 1 of the drawings is a longitudinal vertical section, and Fig. 2 a plan view, of my invention. Fig. 3 is a detail perspective view of the core or shaping-iron.

This invention relates to certain new and useful improvements in harness-pad presses, the object thereof being to construct such a device whereby a perfectly-shaped pad may be obtained free from wrinkles, as by the application of my invention all the stretch is taken out of the leather, the pressure thereon being brought to bear in two directions, vertically and laterally; also, when the pad-piece is suitably pressed and crimped the same is held in place for tacking to the frame, preparatory to stuffing and stitching, without removing said pad from the press. These objects I attain by the construction substantially as shown in the accompanying drawings and hereinafter described.

In the drawings, A represents the mold or press, formed with a depression similar in shape to the contour of the pad. At each end, upon one or both sides of this mold or press, are guide-rods a, screw-threaded at their outer ends, and upon which work a follower, B, operated by a clamping-screw, C, having its bearing in a brace-bar, D, adjustable on the guide-rods by means of the nuts b, working on their screw-threaded ends.

The leather to be pressed is placed in the depression of the mold or press, and a core or shaping-iron, E, similar in shape to the form of said depression, is forced down thereon by means of a hammer, said core or shaping-iron being made solid, so that an even pressure may be exerted on all portions of the leather to prevent the same from being imperfectly stretched, and thereby forming wrinkles, as is frequently the result when the core or shaping-iron is made hollow, such form being usual in the pad-presses now in

ordinary use. After the leather has been crimped into shape by employment of the above-described means the follower B is brought tightly up against the same by means of the clamping-screw C, this side screw pressure taking all the remaining stretch and wrinkles out of the leather, and leaving a perfect well-shaped pad. By taking off the side or lateral pressure by means of the screw the core or shaping-iron E is readily removed and a tack-iron, F, placed in position over the pad-shape, said tack-iron having a projection, c, upon its under side at the rear end, which enters a staple, d, upon the end of the mold or press A, to prevent the iron from being displaced longitudinally. The follower is now tightened up to secure the pad-shape and the frame G laid upon the tack-iron, the surplus leather of the pad-shape extending up beyond the said tack-iron, and frame is now bent down and tacked near the edge of the frame. After the pad-shape has been tacked to the frame the side pressure is released, and said frame with the pad-shape secured thereto and the tack-iron are removed from the press or mold. The tack-iron is now drawn out from between the pad-shape and frame, and the pad is ready for stuffing and stitching, the pad being free from all wrinkles and perfect in shape.

Having now fully described my invention, what I claim as new, and desire to secure by Letters Patent, is—

1. The pad-press A, formed or cast of a single piece of metal, as shown, and provided with staple d at its end, in combination with the solid core or shaping-iron E and tack-iron F, having projection c, substantially as and for the purpose set forth.

2. The pad-press A of the form shown, having lateral screw-threaded guide-rods a, nuts b, and provided with the staple d, in combination with the core or shaping-iron E, tack-iron F, provided with the projection c, follower B, brace-bar D, and clamping-screw C, operating substantially as and for the purpose specified.

In testimony that I claim the above I have hereunto subscribed my name in the presence of two witnesses.

LEWIS H. URNER.

Witnesses:

E. A. DULIN,
JAMES O. LEE.
